UNITED STATES PATENT OFFICE.

CHRISTIAN BERGER, OF NEW YORK, N. Y., ASSIGNOR TO SUBMARINE WIRELESS COMPANY, A CORPORATION OF NEW YORK.

SUBMARINE SIGNALING APPARATUS.

1,187,127.

Specification of Letters Patent. Patented June 13, 1916.

Application filed February 21, 1913. Serial No. 749,829.

To all whom it may concern:

Be it known that I, CHRISTIAN BERGER, a subject of the King of Hungary, residing at New York city, in the county of New York and State of New York, have invented certain new and useful Improvements in Submarine Signaling Apparatus, of which the following is a specification, reference being had therein to the accompanying drawings.

My invention relates to a receiving apparatus or instrument, more particularly, as will hereinafter appear, for the purposes of submarine signaling wherein signal vibrations are transmitted through the water from one vessel or sending point to the receiving point or vessel.

Generally speaking, the objects hereof are to improve the construction of and to increase the efficiency of submarine signal receiving apparatus, and to simplify the same and increase its convenience.

Another object hereof is to provide a superior microphone mounting adapted to be located in a perforation below the water line in the shell of a vessel.

Another object hereof is to afford a superior receiving instrument by which the vibrations detected by the microphone are rendered sensible to the operator.

Other objects hereof will appear in the hereinafter following description, or will be apparent to those skilled in the art of submarine signaling.

To the attainment of the above referred to objects the present invention consists in the novel features of construction, arrangement, combination and operation described or illustrated in the accompanying description and drawings.

I will first describe one form of apparatus embodying my invention and will thereafter point out the novel features in the claims.

In the accompanying drawings forming a part hereof Figure 1 in a diagrammatic way shows a plan view of an apparatus embodying my improvements. Fig. 2 is a detached view of the receiving instrument shown partly in central cross section. Fig. 2^a is an enlarged detail of a portion of Fig. 2. Fig. 3 shows in central cross section the mountings of the sensitive device or microphone which is to detect the vibrations in

the water, the microphone box being shown 55 in exterior view. Fig. 4 shows a similar cross section of the microphone box, an ordinary form of microphone button being shown therein in exterior view.

Similar reference characters designate 60 corresponding parts in the several figures of drawings.

Floating or otherwise immersed in the water 11 of the ocean or other body of water is shown in Fig. 1 the shell 12 of a signal sending ship or station, in which for convenience sonorous vibrations may be created by an instrument such as the vibrating wire or strip 13. The signal receiving station 14 may be a vessel traveling in the direction 70 of the arrow, it having an immersed shell or preferably two immersed shells, 15 on the port side and 16 on the starboard side.

In the shell 15 may be mounted at 17 a microphone or other sensitive device preferably of the type adapted to vary the resistance in an electric circuit for rendering the received signals perceptible; and a second such microphone may be mounted at 18 in the shell 16. The microphones detect 80 the vibrations received from the distant point and the operator receives them by any convenient instrument, preferably by a receiver located at 19 adapted to be held to the ear as an ordinary telephone receiver. 85

The diagram of electric connections is so set that the operator is listening for the vibrations received at 17, and the circuit is as follows: A branch wire 20 extends to the microphone at 17 from a wire 21 which in 90 turn is connected to the switch arm 22 of a switch 23, and thence through the contact 24 and wire 25 to the receiver 19, the circuit being completed by wires 26 and 27 from the receiver to battery 28, and by wire 95 29 to the switch arm 30 of a switch 31 thence through the contact 32 and wire 33 to the microphone at 17. A sonorous disturbance of the microphone at 17 causes variations in the electric current passing therethrough 100 which are rendered audible by the receiving instrument 19.

The switch 31 enables the operator to throw either microphone into connection. Thus, if the switch arm 30 is thrown over 105 to contact 35 the course of the circuit will be altered so as to cut out the microphone at 17 and to throw in the microphone at

13, the latter having a branch wire 34 and a wire 36 corresponding to the wires 20 and 38 for microphone 17.

For the purpose of illustrating that in some cases a transformer or eliminator may be introduced between the microphone and the receiving instrument, I have shown the following further connections: The switch 23 has a contact 37 and when the switch arm 10 22 is thrown thereto the circuit from the microphone 17 will no longer pass to the receiving instrument 19, but will pass through wire 38 to the primary coil 39 of the transformer, thence completing the circuit through connections 27 to 33 inclusive as before. Combined with the transformer primary is a secondary 40 connected by wire 41 with switch arm 42 which will be closed so as to touch the contact 43, which 20 latter is connected by wire 44 with the receiver 19, the wire 26 thence completing the secondary circuit.

One important feature of improvement herein, which I claim not only in combination but as an article of manufacture, is a vibratable diaphragm consisting of the comparatively thin middle portion or membrane and, surrounding it, the integral thick rim, periphery or flange. Such a vibratable diaphragm, which would be useful in various acoustic apparatuses, for example a receiving instrument, I preferably construct by procuring a metallic plate or disk of substantial thickness and then cutting or machining out the middle or interior area thereof to the desired thinness, for example from one-half to one millimeter.

I have herein illustrated employment of this improvement both in the receiving instrument 19 and in the microphone box at 17. There are several important advantages in the novel diaphragm thereof. The integral character of the vibrating membrane and the peripheral flange, which is 45 of substantial thickness and weight, gives the diaphragm great strength to resist wear and injury. It moreover possesses high efficiency and I have discovered that superior acoustic effects are secured. A high 50 frequency of vibration is satisfactorily attained which is of importance for an apparatus of the class referred to. For example, I may attain from one to three thousand vibrations per second with this diaphragm. The improvement also affords a superior mode of mounting and detaching the diaphragm, since it can be very conveniently and effectively secured in place by its flange, which may be generally cylindrical and 55 which may, if desired, be provided with screw threads or the like for locking it in position or for securing other parts that are to be combined with it. Such a diaphragm, for example, is easily constituted as the front 60 wall of a microphone box.

In cases where a vibratable diaphragm is to be employed in an immersed location this improvement enables a nonleaking connection to be readily made. Moreover, there being no joints or perforations or exterior screw heads, there is minimum liability to fracture, and a perfectly smooth flush exterior is attainable so as to avoid vibratory disturbances from the movement of the water. There is no such galvanic action as 75 would exist with a soldered membrane. The diaphragm possesses strength to resist considerable under water pressure notwithstanding its actual thinness; and I find that the strength is increased by the presence of 80 the central integral projection or teat shown for the attachment of the microphone.

Coming now to the receiving instrument 19 it is shown as possessing the usual casing 51 and magnet 52, and it also contains a diaphragm 53 of the character above described having an integral thick periphery or flange 54 extended laterally of the plane of the diaphragm, and a rim 55 by which it may be secured in place by any desired 90 clamping means as ring 56.

Another important feature of improvement hereof is the provision within the marginal clamping device 56, and within the integral flange 54, of a means or device contacting the thin portion of the diaphragm for distending the diaphragm for purposes that will appear. In employing the word "distending" I do so in a broad sense including a stretching of the membrane, or 100 putting it under a special strain or tension, which may be accomplished, for example, by pressing laterally or actually deflecting or bending the membrane from its normal plane, resulting in a tightening or stiffening of the 105 diaphragm.

I find that with this improvement I am enabled to employ an electric current of high intensity and strength in the magnet coils of the receiver 19, which increases the 110 polarization of the magnets and thereby magnifies the action of the device so as to increase the perceptible effect of the microphone connected to the receiver. Moreover, this improvement enables a simple series 115 circuit of the microphone, the battery and the receiver, there being no need of the current eliminations effected by a transformer. Indeed, a current may be used of such strength as would permanently deflect or 120 distort an ordinary diaphragm. This device, which would be applicable to various sorts of receivers, I find also possesses a certain damping effect against low or irregular vibrations so that it materially assists in 125 eliminating disturbing sound and thereby renders the system more sensitive and gives it a greater range of action. By rendering the distending device adjustable I am enabled to alter its pressure upon the dia- 130

phragm and its effect upon the action thereof to suit the circumstances.

A distending device in accordance with this invention and, for convenience, combined with the ear piece of the receiver, may be designed and constructed as shown at 57, Figs. 2 and 2^a. The piece 57 may be adjustably secured in place by its screw threaded portion 58, shown engaging corresponding screw threads at the inner side of the flange 54 of the diaphragm. The actual contacting portion or rim of the piece 57 is shown in the form of an annular rib or bead 59 of a diameter slightly less than 15 that of the diaphragm flange. Screwing the piece 57 forcibly into place causes the contact rim or bead 59 to press laterally against the diaphragm so as to somewhat deflect the middle portion of the diaphragm out of the plane of its margin, thereby distending the diaphragm in accordance with this invention. The locking, or threaded engagement, between the distending device and the diaphragm flange is of importance as insuring 20 a permanent relation between the diaphragm and device when adjusted. The piece 57 may have an outward extension 60 affording an ear opening. It will be noticed that I have secured the advantageous effect due to 25 close proximity of the ear piece and the diaphragm by which the audible effect is magnified, owing to the air vortex produced through the opening 60 when the diaphragm vibrates.

30 Another important feature of improvement hereof is the disclosed construction by which the microphone is mounted in a below water perforation in the shell of the vessel. By such construction the receiving diaphragm, which is immersed in direct contact with the water, is rendered at its front side flush and even with the exterior of the vessel. Neither protuberance nor recess is possible as the diaphragm is exactly maintained in proper position and therefore all rush or whistle of the water is eliminated so that the signaling operations are not disturbed from that cause. This advantageous result is shown as attained by means of the 35 integrally flanged diaphragm the many advantages of which, above recited, pertain to its use in this manner. The structure shows the receiving diaphragm constituted as part of a microphone box capable of being separately handled and attached and detached. Thereby it is rendered simple and easy to mount or remount or replace the box in cases of damage or disorder. The disclosed construction enables and shows complete sound 40 insulation of the microphone box, so that no disturbing vibrations traveling through the shell of the ship may be communicated by way of the microphone to the listening operator. The sound deadening separator or 45 packing also serves to exclude water so that

the microphone box effectually closes the perforation in the ship's side. Referring to Figs. 3 and 4, the shell 15 is shown as perforated at 63 by a preferably circular aperture. In the forward interior is the microphone or button 64. The front wall or receiving diaphragm 65 may be a part of the microphone or may directly carry the button at its rear surface. Herein I will refer to the immersed or water side of the apparatus 70 as the front or forward side and I will use the terms outwardly and inwardly with reference to the axis of the apparatus. The front wall or diaphragm 65 is a constituent part of the microphone box 66 shown in exterior view in Fig. 3 and in cross section in Fig. 4.

The microphone box may be mounted and dismounted without taking it apart. The mountings thereof may be as follows: I 75 prefer first to bring the shell 15 to a standard thickness by securing thereto an annular disk or liner 67, rivets 68 being shown to secure it, and a circular perforation is then bored through shell and disk. A cylindrical 80 piece 69 is then secured in such way as to afford a front flange or rim flush with the shell 15. This member 69 is preferably a cylindrical sleeve or lining fitting within the perforation and having an interior flange 85 at 70 for securing it to the disk 67 by bolts 71, a packing 72 being inserted between them. The lining 69 also has a front flange or rim 73 flush with the shell 15 and with the front wall 65 of the microphone box. A 90 cover or safety cap 76 may be secured to the shell at the rear side not only for the protection of the apparatus but as an additional 95 precaution in preventing leakage; this cover having bolts 77 for securing it in place and having preferably a stuffing box 78 for the passage of the wire or wires 20 and 23 by which the microphone is placed in circuit with the receiving instrument 19.

In attaching the microphone box it 100 cooperates with the parts before described by reason of its general cylindrical shape and an outward flange opposed to the flange 73. The microphone box front wall is the diaphragm 65 having the thin vibratable membrane portion and the thick heavy integral flange 79 at the periphery, which, as well as the central teat 80, project rearwardly. This diaphragm is permanently secured by the screw threads on its flange 79 to the forward end of the barrel 81 of the microphone box.

The electric microphone within the box 110 66 may be of any known form, it preferably comprising a resistance-varying material 115 such as carbon actuated by the vibration of the diaphragm 65; and the same is preferably attached directly at the diaphragm, or even carried by it as shown. For convenience, I prefer to employ a microphone 120 125 130

button such as 64 attached at or secured to the diaphragm.

Formed on the cylindrical barrel 81 of the microphone box is the outward annular flange 82. This forms an efficient means, coöoperating with flange 73, for accurately positioning the microphone box. It will be noted that the flange 79 of diaphragm 65 is not sufficiently large to contact the flange 10 73 of the lining 69. Neither is the outward flange 82 sufficiently large to contact the cylindrical portion of the lining 69.

In order to properly center the microphone box, thus keeping it free from metal-15 lie contact, and in order also to secure its proper position with the vibratable dia-20 phragm flush with the shell 15, I have pro-25 vided a separator 83 composed of sound deadening material such as rubber of ap-30 preciable plasticity, which is shown in the form of an annular packing or washer so that it also serves to preclude leakage. This separator 83 is located between the inward flange 73 and the outward flange 82 and it 35 is preferably of such dimension as to enable it to be preliminarily secured upon the microphone box as shown in Fig. 4.

A convenient means for securing the microphone box in place or pressing it to its 30 seat consists of any suitable locking means adapted to press forwardly, and I prefer to insert a second sound deadening separator or packing 84 between the microphone box and the locking device. Thereby the microphone box is wholly insulated from sonorous 35 contact with the shell 15. To securely lock the parts in place a screw ring or sleeve 85 may be employed which engages threads on the lining piece 69 so that the ring may be 40 screwed forwardly to impose a heavy pressure upon the separators 83 and 84. As shown the separators are confined and the pressure thereby forces them into intimate 45 contact with all surrounding parts so that the microphone box is securely and accurately locked in properly centered position.

Microphone box 66 may be conveniently closed on all four sides. To this end a rear piece or wall 87 is shown which is formed 50 with an interior recess 88 containing an annular lining or support 89 for the shank 90 of the microphone button 64. The piece 89 may be either a sliding bearing or elastic material as rubber, so that the microphone 55 button, which is supported and attached at its forward end to the diaphragm, may be yieldingly supported at its rearward end yet in such manner as to permit relative movement so that any violent movement of 60 the diaphragm 65 is allowed for and breakage prevented.

The rear wall 87 of the microphone box 65 may have a screw cap and stuffing box 91 for the wires 20 and 33. The stuffing boxes 91 and 78 may, for convenience, be of a type

containing compressible rubber pieces 92 which are forced into intimate contact with the wires when put under pressure so that leakage is surely avoided.

It will thus be seen that I have described 70 an apparatus attaining the objects and advantages before referred to, and other advantages will be obvious to those skilled in the art.

Since many features and details may be 75 varied without departing from the principles of the improvements hereof, I do not wish to be restricted to any features or details excepting as set forth in the appended claims. 80

What I claim is:

1. A submarine signal receiving apparatus comprising, in combination with the shell of a vessel perforated below the water line, a microphone box having as a front wall a receiving diaphragm adapted to directly contact the water, said diaphragm having an integral inwardly extending flange by which it is connected as a part of said box, and means for mounting said box in the shell 90 perforation with said front wall flush with the shell so as to preserve the continuity of the shell exterior surface. 95

2. A submarine signal receiving apparatus comprising, in combination with the shell 95 of a vessel perforated below the water line, a microphone box having as a front wall a receiving diaphragm adapted to directly contact the water, said box having an outward flange, an annular member secured 100 to said shell affording an inward flange, said two flanges having their opposed surfaces substantially parallel to each other and to the exterior surface of the shell, a sound deadening separator between said flanges, 105 and means for securing the box in its seat with its receiving diaphragm flush with the shell.

3. A submarine signal receiving apparatus comprising, in combination with the shell 110 of a vessel perforated below the water line, a microphone box having as a front wall a receiving diaphragm adapted to directly contact the water, said box having an outward flange, an annular sound deadening 115 separator on each side of said flange, and means for securing the box to its seat by right-angled pressure upon said separators.

4. A submarine signal receiving apparatus comprising, in combination with the shell of 120 a vessel perforated below the water line, a microphone box having as a front wall a receiving diaphragm adapted to directly contact the water, said box having an outward flange located rearward of said diaphragm, 125 an annular lining piece within said perforation formed with a front flange flush with the shell, an annular sound deadening separator between said two flanges, a second sound deadening separator to the rear of said box 130

flange, and a securing device adapted to maintain said box on its seat by pressure on said second separator.

5. A submarine signal receiving apparatus comprising, in combination with the shell of a vessel perforated below the water line, a microphone box having as a front wall a receiving diaphragm adapted to directly contact the water, said box having an outward flange located rearward of said diaphragm, an annular lining piece within said perforation formed with a front flange flush with the shell, an annular sound deadening separator between said two flanges, a second sound deadening separator to the rear of said box flange, and a securing device adapted to maintain said box on its seat by pressure on said second separator, said device consisting of a screw threaded ring engaged with said lining piece.

6. A submarine signal receiving apparatus comprising, in combination with the shell of a vessel perforated below the water line, a microphone box of cylindrical shape having as a front wall a receiving diaphragm adapted to directly contact the water, and having an outward flange to the rear of said diaphragm, a cylindrical lining sleeve within said perforation having a front annular flange flush with the shell and a rear flange secured to the shell, an annular separator between said sleeve front flange and said box flange, said separator and flanges so constructed that said diaphragm is flush

with said front flange and said sleeve and box are out of contact, a second annular separator located at the rear of said box flange, a screw sleeve engaging within said lining sleeve adapted to press forward on said second separator to put both separators under compression and secure the box in place, said screw sleeve constructed not to contact said box, and an inner cap piece covering said box and secured to the shell.

7. A submarine signal receiving apparatus comprising, in combination with the shell of a vessel perforated below the water line, a microphone box having as a front wall a receiving diaphragm adapted to directly contact the water, said diaphragm consisting of a united vibratable plate and a peripheral inwardly extending flange, said box having an outward flange located rearward of said diaphragm, an annular lining piece within said perforation formed with a front flange flush with the shell, an annular sound deadening separator between said two flanges, a second sound deadening separator to the rear of said box flange, and a securing device adapted to maintain said box on its seat by pressure on said second separator.

In testimony whereof I have affixed my signature in presence of two witnesses.

CHRISTIAN BERGER.
